UNITED STATES PATENT OFFICE.

WILLIAM CLARK WOOD, OF HOBOKEN, NEW JERSEY, ASSIGNOR TO NEW YORK SWITCH & CROSSING COMPANY, OF HOBOKEN, NEW JERSEY, A CORPORATION OF NEW JERSEY.

TONGUE-SWITCH.

SPECIFICATION forming part of Letters Patent No. 790,835, dated May 23, 1905.

Application filed January 4, 1905. Serial No. 239,634.

To all whom it may concern:

Be it known that I, WILLIAM CLARK WOOD, a citizen of the United States of America, and a resident of the city of Hoboken, in the State of New Jersey, have invented a new and useful Improvement in Tongue-Switches, of which the following is a specification.

This invention relates to tongue-switches for street-railway service; and it consists in certain novel combinations of parts hereinafter set forth and claimed.

The leading object of the present invention is to compel the movable point or tongue to lay firmly at either side of the switch-groove without the aid of a "block."

In the improved tongue-switch the tongue is held in its respective positions of rest by an automatic safety device, as hereinafter set forth.

Another object of the invention is to pivot the tongue in a simple and effective manner, said safety device serving to keep the pivot in working condition.

Other objects will be set forth in the general description which follows.

A sheet of drawings accompanies this specification as part thereof.

Figure 1 is a top view of the improved tongue-switch with the cover of the safety-device housing removed. Fig. 2 represents a vertical longitudinal section in an approximately central plane. Fig. 3 represents a cross-section on the line A B, Fig. 1. Fig. 4 is a top view of the tongue detached. Fig. 5 represents a cross-section on the line C D, Fig. 4; and Fig. 6 represents a cross-section on the line E F, Fig. 4, said cross-sections being drawn on a larger scale.

Like reference characters refer to like parts in all the figures.

The body *a* of the improved switch and the connections of said body with the adjoining rails 1, 2, and 3 may be of any known or improved description. Within the switch-body *a*, and preferably and conveniently in part within a steel center *b*, the movable point or tongue *c* is arranged, as shown in Figs. 1 and 2, so as to be movable horizontally in custom-

ary manner. This tongue is preferably of the shapes in cross-section illustrated by Figs. 3, 50 5, and 6, but may be of any known or improved construction apart from the features hereinafter specified and included in the appended claims, respectively.

For pivoting the tongue *c* its heel end is 55 constructed with a peculiarly-beveled knuckle 4, fitted to an undercut pivotal recess 5 in the adjoining edge of a steel heel-cap *d*, which is fastened in place by vertical bolts *e*, having nuts *f*, Fig. 2, at the bottom of the switch-body.

For holding the tongue *c* in its respective positions of rest, the tongue itself is provided at or about mid-length, hereinafter described as at mid-length, with a downwardly-projecting stud-pin 6. (Shown in dotted lines in Figs. 1 and 4 and in the plane of section in Fig. 2.) This "shifting pin" 6 is pivotally connected with a laterally-extending lever or "shifting bar" 7, having conveniently a notch 8 opening 70 toward the heel end of the tongue to engage said pin. At one side of the switch-body *a* and bolted thereto a housing-box *g*, open at the top, incloses the remainder of the safety device, as shown in Fig. 1, which see. The other end of 75 said shifting bar 7 is pivotally connected to a horizontally-swinging clevis 9, whose other end is pivoted to a fixed support 10, bolted fast within said box *g*. At an intermediate point and preferably at mid-length the shifting bar 80 7 is pivotally connected with one end of a spring-strut 11, containing a compression-spring *h*, which tends to hold the tongue *c* in either of its two positions of rest and in connection with said clevis 9 forms an untenable 85 center for the tongue, so that it cannot rest at the middle of its travel. The other end of said spring-strut 11 has a knuckle-bearing 12, bolted fast within said box *g*. A screw-nut *i* provides for regulating the tension of the 90 spring *h* in assembling the parts of the device. Ordinarily it will require no further attention.

Owing to the construction above particularly described, when the point of the tongue 95 *c* is moved from either of its positions of rest

past the center of its travel its movement is instantly and effectively completed by said safety device, and it is securely held in its new position of rest until the resistance of the 5 spring *h* is overcome.

When the tongue *c* is moved by means of the switch-iron to the center of its travel, the safety device gives it, in other words, an inclination to complete the movement and holds 10 the tongue firmly in place against the side of the groove toward which it was moved, so that all the wheels of the car passing over it must take the same run and the spring *h* must be compressed in order to move the 15 tongue *c* to the opposite side or away from the position of rest in which it is thus placed. At the same time the pressure of the spring *h*, acting through that end of the strut 11 that is attached to the shifting bar 7 and 20 through said shifting bar 7 and shifting pin 6, tends to keep the bevel of the pivotal knuckle 4 in place within the pivotal recess 5 of the heel-cap *d*, so as to obviate the employment of other means for preventing the longitudinal 25 displacement of the tongue *c*. It also tends to hold the tongue *c* firmly down upon its bed formed in part by said steel center *b* and to maintain an efficient joint between the heel-cap *d* and the tongue *c*.

30 Instead of being arranged within a strut, as above described, the spring *h* may be applied to the opposite edge of the shifting bar 7 in the form of a tension-spring, or the spring *h* may be placed directly under the tongue *c* either in front of the shifting pin 6 or behind the same; but I find in practice that it is preferable to use the shifting bar, clevis, and spring-strut housed within a suitable box bolted to one side of the switch-body, as above 35 described. The clevis 9 makes said untenable center very acute or sensitive. It also forms a strut or brace opposite the spring-strut 11 and constitutes the fulcrum of the shifting bar 7. Other forms of movable fulcrum may, however, be substituted for said 40 clevis 9, and other like modifications will suggest themselves to those skilled in the art.

Having thus described said improvement, I claim as my invention and desire to patent 45 under this specification—

1. The combination, substantially as hereinbefore specified, of a switch-tongue having an undercut pivotal bearing at its heel end and having the customary horizontal travel 55 from one position of rest to another, and a safety device for insuring completed movements of the tongue, said safety device including a horizontally-arranged spring acting upon said tongue and tending to hold the 60 tongue in one or the other of its positions of rest and also to press the heel end of said tongue into such pivotal bearing.

2. The combination, substantially as hereinbefore specified, of a switch-tongue having the 65 customary horizontal travel from one position

of rest to another, and a safety device for insuring completed movements of the tongue, said safety device comprising a horizontally-movable shifting bar one end of which is pivotally connected with said tongue, a clevis 70 pivoted to the other end of said bar and forming a horizontally-movable fulcrum therefor, and a horizontally-arranged spring acting upon said bar and tending to hold the tongue in its respective positions of rest. 75

3. The combination, substantially as hereinbefore specified, of a switch-tongue having the customary horizontal travel from one position of rest to another and provided at mid-length with a downwardly-projecting shifting pin, 80 and a safety device for insuring completed movements of the tongue, said safety device comprising a horizontally-movable shifting bar one end of which is pivotally connected with said pin, a clevis pivoted to the other 85 end of said bar and forming a horizontally-movable fulcrum, and a horizontally-arranged spring acting upon said bar and tending to hold the tongue in its respective positions of rest. 90

4. The combination, substantially as hereinbefore specified, of a switch-tongue having the customary horizontal travel from one position of rest to another and provided at mid-length with a downwardly-projecting shifting pin, 95 and a safety device for insuring completed movements of the tongue, said safety device comprising a horizontally-movable shifting bar one end of which is pivotally connected with said pin, a clevis pivoted to the other 100 end of said bar and forming a horizontally-movable fulcrum, and a horizontally-arranged spring acting upon said bar and tending to hold the tongue in its respective positions of rest, and a laterally-projecting box forming 105 a housing for said shifting bar, clevis and spring, and provided with fixed supports for said clevis and spring respectively. 110

5. The combination, substantially as hereinbefore specified, of a switch-tongue having the customary horizontal travel from one position of rest to another and provided with a downwardly-projecting shifting pin, a laterally-projecting shifting bar movable horizontally and pivotally connected at one end to said pin, 115 a horizontally-swinging clevis pivoted to the other end of said bar at one edge thereof, a spring-strut provided with a compression-spring and pivotally connected with said bar at mid-length at its opposite edge, and a box 120 forming a housing for the laterally-projecting parts and provided with pivotal bearings for said clevis and strut respectively. 125

6. The combination, substantially as hereinbefore specified, of a switch-tongue having an undercut pivotal bearing at its heel end, a horizontally-movable shifting bar pivotally coupled to said tongue at one end, a horizontally-swinging clevis pivoted to the other end of said bar and forming a horizontally-movable 130

fulcrum, and a horizontally-arranged spring acting upon said bar at mid-length and tending to hold the tongue in one or the other of its positions of rest and also to press the heel end 5 of said tongue into its said pivotal bearing.

7. The combination, substantially as hereinbefore specified, of a switch-tongue constructed with a beveled knuckle at its heel end, an undercut cap interacting with said knuckle as 10 the pivotal bearing of said tongue, a horizontally-movable shifting bar pivotally coupled to said pin at one end, a horizontally-swinging clevis pivoted to the other end of said bar, and a horizontally - arranged spring acting 15 upon said bar at mid-length and tending to hold the tongue in one or the other of its positions of rest and also to press the heel end of said tongue into its said pivotal bearing.

8. A tongue-switch having, in combination, 20 a horizontally - movable tongue constructed

with a beveled knuckle at its heel end and provided with a downwardly-projected shifting pin at mid-length, an undercut cap interacting with said knuckle to form the pivotal bearing of said tongue, a laterally-projecting 25 shifting bar pivotally coupled to said pin and movable horizontally, a clevis pivoted to the other end of said bar and forming a movable fulcrum at one edge of the same, a horizontally-arranged spring-strut inclosing a compression-spring and arranged at the other edge 30 of said bar at mid-length, and a box housing said shifting bar, clevis and spring, and provided with pivotal supports for said clevis and strut respectively, substantially as hereinbefore specified. 35
